UNITED STATES PATENT OFFICE

ARCHIBALD G. SHAVER, OF CHICAGO, ILLINOIS

TRAFFIC CONTROL SYSTEM

Application filed June 14, 1927. Serial No. 198,824.

My invention relates to improvements in means for operating a track switch from a train.

It is the usual practice on railroads for a train desiring to enter or leave the main line at a siding to stop while a member of the crew walks ahead and operates a switch, except where the switch is connected with a tower or station and controlled by an operator. In the case of heavy freight trains in particular, the stopping and starting of the train involves a great loss of energy, in addition to the time loss. In practicing my invention, these losses are eliminated by the provision of improved and efficient means for operating the switch without stopping the train.

One object of my invention therefore is to provide improved means for operating the track switch from the train, for example from the cab of the locomotive, without bringing the train to a stop.

Another object is to provide means whereby the track switch may be manually controlled from the train, from normal position to the reverse and automatically returned from reverse to normal position as soon as the train has cleared the track section in which the switch is located.

Another object is to provide practical means, active for a predetermined time interval, for operating the switch from the moving train through inductive means and without the necessity for physical contact between some parts carried by the locomotive and a stationary part on the road-side.

Another object is to make more practical and certain an arrangement whereby the operation of the track switch from the moving train is dependent upon the speed of the train to insure that the train will slow down before taking the siding.

A further object is to provide means whereby, in connection with a spring connected track switch, a train on the main line may operate said switch and enter the siding, and after clearing the track circuit section, the switch will return automatically to normal position, after which the train may move back onto the main line, again running

through the points of the switch when in normal position without danger to said points.

A further object is to provide means whereby the engineman, when he acts to set the track switch for the siding, will be advised by a signal indication that the switch controlling means has started to function.

A further object is to provide means in a system, such as described, for informing the engineman when the track switch is in proper position for the train to pass over it.

An additional object is to provide in a system, such as described, means for preventing the switch from being operated when the track, including the switch and adjacent siding, within the fouling points, is occupied by a train.

An additional object is to provide means whereby the main line signal indicates in the "stop" position before the operating mechanism for the switch can begin to function.

An additional object is to provide means whereby a train may automatically operate the switch in passing from the siding to the main line.

Other objects will appear from the drawing and accompanying descriptions relating to one embodiment of the invention.

Figure 1 shows the circuits and controlling devices on the locomotive and on the road-side.

Figure 2 shows a modified track inductor circuit.

The track is divided into the usual track circuit sections S, S1, S2, S3, etc. Each section is provided with a battery and a relay. For example, the section S1 is provided with a battery B1 and a relay R1. Section S2 is provided with a battery B2 and a relay R2. The track circuit section S2 includes the siding as far as the fouling point F. This siding has the usual switch SW which is controlled by a combined switch stand and selector SS. A spring s is connected in the control rod of the switch in the usual way so that the switch points will not be damaged when the switch is run through trailing.

The switch is actuated by a motor M which drives suitable power mechanism PM for

opening or closing said switch. The arrangement is such that either the switch stand or the power mechanism may be connected to the switch to permit manual or power operation. Before describing the circuits for actuating the motor, the circuit on the locomotive will be described.

The locomotive carries an inductor I, suitably located so as to pass near the stationary inductors I1 and I2 without contacting with the same, the purpose being to induce a momentary current in the stationary inductors. The inductor I may be energized by any suitable source of current, such as the generator G, provided the hand-switch H is closed to complete the circuit through the conductors 10. The generator G may be either fluctuating or alternating current, direct current, or a battery may be employed. Switch H is preferably of the type which, after being manually operated automatically holds itself closed a predetermined length of time, or it may be of the impulse type so that it cannot be held or fastened in closed position, an example of the impulse type being shown in my pending application, Serial No. 634,053 filed April 23, 1923.

The stationary inductor I1 is connected in series with relay R4 by means of conductors 11, 12 and 13, said circuit being normally open, however, at the switch 14. Said switch is closed whenever the relay R3 is energized by current from the battery B3, the circuit of said relay through conductors 15 and 16 and switch 17, however, being normally open at said switch when no train is in the section. Relay R3 is for closing its contact 14 at the end of a specified time only, such type of relay being well known commercially as a "time relay". Under normal conditions, the relay R1 is energized by current from the battery B1, but whenever a train enters the section S1, the relay R1 is short-circuited, the relay R3 energized, and thus the circuit to the relay R4 is closed, whereby the inductor I carried by the locomotive, may pass the stationary inductor I1 and induce sufficient current in the circuit of the relay R4 to energize the latter, thereby closing the motor circuit, as hereinafter described.

The train should enter the siding at a speed less than that generally maintained on the main line. The equipment is so designed that a train about to operate the track switch to enter the siding must consume a greater period of time passing through that part of the track section S1, indicated as Z, than the time required for the relay R3 to close the circuit controlled thereby. The circuit of the relay R3 is so designed as to require an appreciable time interval to operate it so that if the locomotive reaches the stationary inductor too soon, i. e. at too high a

speed, said relay will not have been operated to close its contact 14. In this way, the engineman is compelled to decrease the speed of the train to at least the predetermined limit to insure entering the siding. The inductor I1 is located within the limits of the track circuit section S1 and far enough away from the signals hereinafter described to give time enough for the switch to move to operated position, and the corresponding signals to give the proper indication. 70

The relay R3 may be adjustable as to the time consumed in closing its contact 14 so that in one installation this time for closing contact 14 may be of one value and in another installation it may be of another value. Thus it is seen that the speed of the train approaching the switch may be regulated to suit the angle of the turnout for the branch line or siding. 80

The circuits for controlling the motor will now be described. The motor is controlled by the relay R6, actuated by current from the battery B4 or other source of energy, the circuit from one terminal including the conductor 17 and parallel circuits 18, 19, which re-unite in the conductor 20 and extend through conductor 21 and control relay R6, through the return circuit 22, movable contact 23 of the track relay R2, and conductor 24 to the other terminal of the battery. The parallel circuits 18 and 19 are normally maintained open by the movable contacts 25 and 26. In order to operate the motor to open the track switch, either the contact 25 or 26 must be closed. As previously pointed out, the train entering track circuit section S1 will cause the energization of the relay R4, thereby closing the circuit of the relay R6 at the contact 25, and opening the track switch. When the train enters track section S2, the relay R2 is de-energized, thereby opening all the circuits through its contacts, including contact 23, thus de-energizing the relay R6 and opening the motor circuit. 100

When the train has passed over the switch SW and has cleared the fouling point F, which is also the end of the track circuit in the siding, the relay R2 is again energized, thereby completing the motor circuit through the contact 23 and restoring the switch mechanism to normal, closed or main track position. The motor rotates in the reverse direction during such operation by virtue of a well known switching mechanism CC. This switching mechanism or circuit controller, CC is so arranged that, as the motor M is completing its rotation in one direction in the opening of the track switch, CC is moved to complete the motor circuit through conductor 49, leading to back contact 27, for closing the track switch SW; and when the motor M again rotates in the opposite direction, it leaves the circuit controller CC in position closing the circuit for motor M through conductor 120

115

120

125

130

ductor 31 for again opening the track switch.

It will be noted that when the control relay R6 is energized, it opens the circuits of the back contacts 27 and 28, and closes the circuits of its front contacts 27 and 29. The closing of the front contact 29 permits battery current to flow through the relay R6 sticking it in a closed circuit, even though the contacts 25 or 26 should open.

In other words, the relay R6 remains energized after either the relay R4 or R5 is energized and until the relay R2 is de-energized.

The circuit arrangement is such that the motor does not begin to operate to open the switch until the necessary stop signal has been displayed. The motor circuit is from the battery B4, through conductor 30, switching mechanism CC, and motor M returning through switching mechanism CC, conductors 31, circuit controller 32, front contact 27, when closed, conductor 22, contact 23, and conductor 24 to the battery. When the relay R2 is re-energized, that is, after the train has passed out of the section S2 into the siding, the return circuit from the motor is by way of switching mechanism CC and back contact 27 to the battery through conductor 22, contact 23, and conductor 24.

Means are provided whereby the engineer-man will be advised by signal indications that the switch operating means has started to function, or that the track switch is in proper position for the train to pass over, or that the switch is properly positioned to permit a train to pass from the siding to the main line. These signals are indicated diagrammatically on the drawings as 33, 34 and 35. They are controlled by two circuit controllers SC and SO, actuated by the same mechanism which actuated the switch. In the drawing, the controller SC indicates the condition of the circuits when the switch is in normal position, and SO indicates the closed position of said circuits only when the switch points are properly locked in either position.

Signal 33 indicates that the main line is open, i. e. that the switch is in the closed or normal position. Signal 34 indicates that the switch is open from the main line to the siding. Signal 35 indicates that the switch is properly set for a train to move from the siding to the main line. The switch must be properly positioned and locked before any signal can give the necessary indication to proceed.

The circuit for signal 33 is from common conductor C connecting to the battery through the controlling mechanism of the signal, conductor 36, closed contact 37, conductor 38, circuit controller 39, closed when the track switch is normal, conductor 40, circuit controller contact 41, closed when the switch is locked, back contact 28 in closed position, and conductor 42, continuing through other controlling elements of the

block, if any, to the battery. It will be noted that this main line signal 33 is open at contact 28 when control relay R6 is energized, thus causing said signal to indicate "stop", and to close the circuit controller 32, either mechanically or electrically, in a well known manner. It will thus be seen that this signal must indicate "stop" before the motor can begin to open the switch.

The circuit for signal 34 may, in like manner, be traced through contact 43, when closed, contact 44, normally open, but closed when the switch is reversed, and contact 45.

The circuit for signal 35 is from the common conductor connecting to the battery, through the controlling mechanism of the signal, and through contact 46, closed when the switch is positioned and locked, contact 47, closed only when the switch is open, contact 48, when closed, and on through other controlling features of the block, if any. The contacts 37, 43 and 48 are controlled by the relay R2, as well as the contact 23 as previously explained.

The detailed operation of the system will be apparent from the foregoing description. A train should enter a passing siding at a less speed than that generally maintained on the main line. The engineman may determine the proper rate of speed to use in approaching the inductor I1 by observing and being governed by the speed indicator SI. After the switch H is closed and the train passes said inductor at the proper speed, the track switch and the signals are operated as previously described. When the train has passed over the switch and cleared the fouling point, the switch is returned to normal or main track position. A train on the siding desiring to come out on the main line also operates the switch SW in response to the closing of the circuit of inductor I on the locomotive and the co-operation of said inductor with stationary inductor I2.

Where switch H is of the predetermined time interval type, it must be closed so that it will maintain inductor I energized during the time that said inductor is in inductive relation with a wayside stationary inductor, as I1 and I2. The use of a train switch H, of the type that will automatically release itself after a predetermined time, has the advantage that the time of an attendant is not required to open said switch after an operation of the track switch has been completed. Further, wrong operation of track switches is avoided in case of forgetfulness on the part of the attendant, as might be the result if switch H was entirely manually controlled for both closing and opening.

Inasmuch as the track switch has the spring connected head-rod, a train may enter the main line from the siding without operating the track switch mechanism, trailing through

the points of the track switch without injury to the equipment.

If, for some reason, a short circuit should occur on the electrical equipment on the locomotive, and the inductor I should become permanently energized, so as to affect the stationary inductor II, such unintentional co-operation could not be effective to operate the track switch unless the speed of the train should be below the prescribed rate, and in such case the speed would be low enough to avoid detrimental results.

It will be seen that the switch is controlled by inductive means, i. e. current induced in a stationary circuit by a moving circuit, as distinguished from mechanical means or electromagnet means, although certain phases of the invention may be used without reference to manner in which the stationary circuit is closed by the moving train.

It has been mentioned that the locomotive circuit may use alternating current in which case it may be desirable to insert in series with the track inductor a condenser X to make the circuit wholly or partially resonant. This is shown on Fig. 2.

What I claim as new is:

1. The combination with a main track and a siding track and a switch connecting the two, of speed governed inductively actuated means for operating said switch in one direction on the approach of a train, and track circuit controlled means for operating said switch in the other direction after the train has passed the same either from the main line to the branch track, or vice versa.

2. The combination with a main track and a siding track and a switch connecting the two, of speed governed inductively actuated means for operating said switch in one direction on the approach of a train, track circuit controlled means for operating said switch in the other direction after the train has passed the same either from the main line to the branch track, or vice versa, and signals for indicating the position of the switch.

3. In combination, a track switch, a motor for operating the switch, a local relay for controlling the motor, a circuit for the local relay, a source of current for said circuit, contacts of two additional relays in parallel circuits between said source of current and said local relay, either of which may close the circuit to said local relay, and a stationary inductor on each side of said switch for causing the energization of one or the other of said additional relays, and an inductor on the moving train for inducing energy into either stationary inductor.

4. A system of the character described, a track having an insulated section, a relay connected to said section and controlling a circuit having a time relay therein, an inductor connected in a second circuit, which is con-

trolled by said time relay, and so positioned with reference to the end of said section as to insure a predetermined rate of travel of the train in order that said time relay may operate to control said second circuit before said train passes said inductor to influence the same.

5. In a system of the character described, an electric motor, a relay therefor, a circuit for said relay, a contact in said latter circuit to close the same, a second relay controlling the foregoing contact, an inductor in circuit with said second relay for energizing said second relay, and a train operated time relay controlling the energizing of said second relay.

6. A railroad switch operating system comprising signals governing traffic over the switch, a mechanism for opening and closing the switch only operative for opening the switch when one of said signals indicates "stop", a relay controlling the operation of said mechanism, and speed governed train means controlling said relay.

7. A railroad switch operating system comprising a switch, a signal governing traffic over said switch, mechanism for opening said switch, a device controlling the operation of said mechanism, and train operated speed governed inductive means controlling the operation of said device, said mechanism being operative to open said switch only when said signal is at "stop" and said device is energized.

8. A railroad switch operating system comprising a mechanism for opening the switch, a signal governing traffic over said switch, a device controlling both said signal and said switch, and means, operative from the train and dependent upon the speed of the train, for controlling said device.

9. In a switch operating system, a mechanism for opening the switch, a signal governing traffic over the switch, and means controlling the operation of said mechanism comprising, a circuit contact associated with said signal, and a train carried means in combination with roadside means, including a track circuit means, effective only in operating said mechanism to open said switch when said track circuit means is de-energized.

10. In a switch operating system, a mechanism for opening the switch, a signal governing traffic over the switch, and means controlling the operation of said mechanism comprising, a circuit contact associated with said signal, and, in combination, a train carried means and a roadside means, including a plurality of track circuit means, same being effective to operate said switch only when one of said track circuits is de-energized and another is energized.

11. A railroad switch operating system comprising a mechanism and a circuit therefor for opening and closing the switch, a

5 track circuit relay and a local relay, each controlling said mechanism circuit to open the switch, and train carried means in co-operation with other track circuit means for controlling the operation of the local relay, effective in said control only when said other track circuit is occupied by a train.

10 12. In combination, a section of railway track, a switch in said section leading to a diverging route, a first signal governing over said switch on the main line, a second signal governing over said switch to the diverging route, a power switch mechanism, including a motor and a circuit for said motor for operating said switch, a local relay which, when energized, sets said main line signal at stop and closes said motor circuit, said circuit being effective to cause operation of said mechanism to open the switch only after said signal indicates stop, a track relay for said section of track controlling said signals, said motor circuit and said local relay, an inductor energized relay inductively controlled from a train source of energy also controlling said local relay, and means operative by said switch mechanism adapted to cause said second signal to operate when said switch has opened.

13. A railroad switch operating system comprising, mechanism for opening the switch, a signal for governing traffic over said switch, a device controlling both said signal and said mechanism, and train carried means, adapted to be set for a predetermined period of activity, for actuating a trackside means on coincidence to control said device.

14. A railroad switch operating system comprising, mechanism for opening the switch, a signal governing traffic over said switch, and train carried means, adapted to be active for a predetermined period, co-operating with roadside means to operate said switch effective only when said signal indicates stop.

15. In a railroad switch operating system in combination, a stretch of track including a switch, a track circuit for said stretch, including a relay therein, a signal governing traffic over said switch, a mechanism for operating said switch including a motor and a circuit for said motor, a circuit contact associated with said signal located in said motor circuit and closed when said signal indicates stop, a contact operative by said track relay also in the motor circuit and other trackside means adapted to be influenced by a train carried means controlling the operation of said motor.

16. In a circuit system of the character described, a motor for operating a track switch, a signal associated with said switch, a local relay having a movable contact and two stationary contacts, each connected in circuit with the motor to open and close the switch, a circuit for said local relay, two relay con-

tacts, each controllable from a train, in said local relay circuit, and a circuit controlling device associated with said signal also in circuit with said motor, the opened and closed positions of said device corresponding to the proceed and stop indications of said signal.

17. In a system for operating a track switch from a train, means on a train for controlling the operation of said switch, comprising, an inductor for producing trackside operation from said train, a circuit for said inductor, a source of fluctuating energy in said circuit, and a switch in said circuit adapted, when closed, to close said circuit and maintain said circuit closed a predetermined time.

18. In a system for operating a trackside relay from a train, trackside means comprising, an inductor and a condenser in circuit with the trackside relay, and train carried means comprising, an inductor in circuit with a source of fluctuating energy, and a switch, adapted, when closed, to maintain said train inductor energized a predetermined interval of time, said train inductor on coincidence with said trackside inductor energizing said relay.

In testimony whereof, I have subscribed my name.
